UNITED STATES PATENT OFFICE.

GEORGE P. BOSWORTH, OF CENTRAL FALLS, RHODE ISLAND, ASSIGNEE TO HEMPHILL COMPANY, OF CENTRAL FALLS, RHODE ISLAND, A CORPORATION OF MASSACHUSETTS.

SEAMLESS STOCKING AND METHOD OF MAKING THE SAME.

Application filed October 14, 1922. Serial No. 594,519.

To all whom it may concern:

Be it known that I, GEORGE P. BOSWORTH, a citizen of the United States, and a resident of Central Falls, in the county of Providence and State of Rhode Island, have invented an Improvement in Seamless Stockings and Methods of Making the Same, of which the following description in connection with the accompanying drawings is a specification, like characters on the drawings representing like parts.

This invention relates to stockings and to the method of making the same.

In order that the principle of the invention may be readily understood, I have disclosed in the accompanying drawing one embodiment of the invention and will describe the best mode known to me for practising the same.

20 In the drawing,—

Fig. 1 is a side elevation of one embodiment of my invention;

25 Fig. 2 is a somewhat diagrammatic representation indicating one manner of knitting the reinforcing stripe at the rear of the stocking; and Figs. 3 and 4 are details in side elevation representing modifications hereinafter referred to.

30 Referring to the single embodiment of the invention selected for illustration, the stocking may be begun at the top 1 of the leg or at the top 2 of the toe. I will first describe the stocking as knitted beginning at the top of the leg upon a circular series 35 of needles which may be of any type, but which preferably are spring beard needles mounted for independent reciprocation in the grooves of the needle cylinder of any suitable machine, such, for example, as a 40 Banner machine, which may make the foot by rotary work or may make a so-called split foot stocking. Any suitable number of needles may be employed and the relative number used in making the different 45 parts may be varied. The numbers hereinafter given are by way of example merely.

It will be assumed that the knitting is commenced upon a circle of 240 needles, and is continued down by rotary knitting to the top of the heel at the line 3, 4, 50 though within the scope of my invention split work may be commenced at any desired point in the ankle, in which case the tapered high splice may be formed prior

to the commencement of split work, and as hereinafter indicated, the high splice may be formed by reciprocating work. In the present disclosure, however, while I have indicated by the line 4, 5, the formation of the foot by split work, I have not indicated the formation of the ankle by split work, though, as stated, this may be done.

Desirably beginning either at the extreme top of the stocking or at the bottom of the welt or garter portion of the stocking (the latter being shown in Fig. 1 and the former in Fig. 3), I form a reinforcing stripe 6 extending as shown from the point 7 at the bottom of the welt or garter portion to the point 8 which is at the apex of the pointed or triangular high splice reinforcement 9. The said stripe 6 may be formed in any suitable manner, but preferably by introducing a reinforcing yarn 10 to or with the main yarn 11 for a suitable number of 75 needles at both sides of the back median line 12 of the stocking. The said reinforcing yarn 10 may be interknitted with the needles throughout the lateral and longitudinal extent of the stripe from edge to edge of said 80 stripe, and at the end of each series of loops in a course of said stripe, said reinforcing may be floated back as indicated at 13 to the opposite edge of the stripe so as to reintroduce the yarn for the next partial 85 course of the stripe.

The reinforcing yarn 10 may be introduced to the needles in any suitable manner, as by means of a special or separate 90 yarn guide or finger, a cam being provided to divide the needles so as at the proper point to leave elevated only those needles which are to take the reinforcing yarn, said 95 yarn and the main yarn being interknitted at the knitting point.

Desirably I provide a mock seam along the median line of the stripe 6, such seam being of any suitable character as, for example, a line of sewing machine stitches or a line of tuck stitches formed during the knitting operation. I have indicated a mock seam of either type at 14 in Fig. 1. For the details of both said types I refer to the patent to Rufus W. Scott, No. 1,491,757, dated April 22, 1924. If a mock seam of 100 sewing machine stitches be employed, the stocking after completion or removal from the knitting machine is run through a suit-

able sewing machine, and the floating threads 14 may be manipulated or supported as desired during the sewing operation.

It will be assumed that the knitting has been completed of a rotary character down to the point 8 and that the stripe 6 has been formed therein. I now proceed to form the pointed or triangular high splice reinforcement 9. While this may be done by introducing the reinforcing thread 10 for successively greater portions of a series of partial courses from the point 8 down to the line 3, 4, I preferably proceed in a different manner, as follows:

15 I now throw out of action while permitting them to retain their loops, the front half of the needles or so-called instep needles, about 120 in number in the present example, and extending from the point 4 20 around to the corresponding point at the opposite side of the stocking as indicated by the line 15. In addition I throw out of action at each side of the back half of the needles, about forty-eight needles in the 25 present example, extending from the point 8 at each side of the stocking, over to the series of instep needles. This leaves in action, according to the present example, about twenty-four needles at the back of 30 the stocking, but this number may be less or more, depending upon the width of the stripe 6. The number of needles remaining in action should, for the best results, be the same number, and in fact the same needles 35 to which the reinforcing yarn 10 was presented. The knitting has at this time been completed down to the line 8, 4, 15. This angular line is, while the stocking is in the machine, a transverse line, but after the 40 stocking has been removed from the machine and washed and boarded, such angular line assumes the direction or position indicated in Fig. 1.

I then knit reciprocatingly upon said 45 twenty-four or other selected number of needles, and then widen by bringing into action an additional needle at each end of the active series in successive courses, thus 50 effecting a widening from the point 8 to the point 4 on each side of the stocking along the inclined suture seam 8'. This creates a 55 gore which is an integral continuation of the tubularly knit portion of the stocking and which is as herein shown of a tapered form. 60 The yarn or yarns employed in knitting said gore or tapered high splice 9 may be the main yarn 11, and the reinforcing yarn 10, or a different reinforcing yarn may be substituted for the formation of the gore 9, 65 being employed with the main yarn 11.

When I begin to knit the gore or high splice 9, I desirably shorten the stitch length for the entire ankle portion, so as somewhat to shape the stocking in this way.

65 Upon the completion of the gore or high

splice 9, I then form the heel pocket 16 in the usual manner by narrowing and widening, and I then form the foot either by rotary work upon the entire series of needles, or by split work in which case the top 17 70 of the foot and the sole 18 are produced by separate yarns connected along the suture line 19 at each side of the foot. In either case the instep needles are restored to action upon the completion of the heel along the 75 line 15. The toe 20 is formed in the usual manner by a narrowing and widening action, and the stocking is seamed along the top of the toe.

The stocking is desirably knitted of silk 80 excepting for the reinforcing yarns, and excepting for the sole of the foot, if the foot be formed by split work. After the stocking is knitted, it is preferably boiled to remove the gum from the silk and may be dried 85 upon a forming board. I have stated that the stitches for the gore 9 may be shortened. In addition thereto or instead thereof I may and preferably do shape the back of the 90 ankle by cutting out a narrow strip at the extreme back of the high splice or gore 9 and extending the length of such high splice or gore, as indicated at 21 in Fig. 4, and then I seam up the same, and in such case such seam constitutes a portion of or merges into 95 the mock seam 14 if the latter be made as a line of sewing machine stitches.

Instead of beginning the knitting at the top of the leg the operation may be reversed and the knitting begun at the toe, in which case the series of steps described would be reversed and need not be described in detail, it being merely necessary to state that when the top of the heel is reached, I proceed by a narrowing action to form the gore or high splice 9, after the completion of which the needles which have been thrown out of action and which retain their loops are restored to action, the instep needles being also restored to action, and then the 100 knitting of the leg and including the front part of the ankle is proceeded with, the stripe 6 being formed as already described. When knitting in this manner the gore or 105 high splice 9 may be shaped in any of the 110 ways already described. It will be noted that if the gore or high splice 9 be formed either by a widening or by a narrowing action, the seam upon each side of the stocking extending from the point 8 to the point 115 4 is an actual narrowing or widening seam, and therefore gives a better finish or produces a better effect than in the case of the raw ends of a splicing yarn severed to remove the floating yarns.

The reinforcing yarn used in knitting the gore or high splice 9 may be continued down through the narrowed portion of the heel, whereupon another yarn may be substituted, or the said reinforcing yarn used in knitting 120 125

the gore or high splice may be continued part way down the narrowed portion of the heel, so as to furnish a drop heel effect.

Having thus described one embodiment of my invention and the best mode known to me for producing the stocking of my invention, I desire it to be understood that although specific terms are employed, they are used in a generic and descriptive sense and not for purposes of limitation, the scope of the invention being set forth in the following claims.

Claims:

1. A seamless stocking having a heel 15 formed of fashioned partial courses and also having at the rear thereof a relatively narrow reinforcing stripe extending substantially throughout that portion of the stocking exposed in wear, said stocking also 20 having a tapered gore of extra partial courses of varying length just above the heel and there constituting a tapered high splice and also constituting a continuation of said reinforcing stripe and of substantially 25 the width of said stripe at the apex of said high splice gore.

2. A seamless stocking having a heel formed of fashioned partial courses and also having at the rear thereof a relatively 30 narrow reinforcing stripe extending substantially throughout that portion of the stocking exposed in wear, said stocking also having a tapered gore of extra partial courses of varying length just above the heel 35 and there constituting a tapered high splice and also constituting a continuation of said reinforcing stripe and of substantially the width of said stripe at the apex of said high

splice gore, said stocking also having a mock seam extending along the median line of 40 said stripe and of said high splice gore.

3. That method of knitting a stocking comprising knitting a tubular leg and during the formation thereof introducing a reinforcing yarn to a relatively small number of needles at the back of the leg to form a relatively narrow lengthwise stripe extending substantially throughout the length of the stocking exposed in wear to the top of the high splice area, and also forming a 50 tapered high splice reinforcement as a gore by a widening operation, thereby providing a tapered high splice gore having sloping seamed edges extending to the top of the heel and knitting the heel by a narrowing 55 and widening operation.

4. That method of knitting a stocking comprising knitting a tubular leg and during the formation thereof introducing a reinforcing yarn to a relatively small number of needles at the back of the leg to form a relatively narrow lengthwise stripe extending substantially throughout the length of the stocking exposed in wear to the top of the high splice area, and also forming a 60 tapered high splice reinforcement as a gore by a widening operation, thereby providing a tapered high splice gore having sloping seamed edges extending to the top of the heel, and knitting the heel by a narrowing 70 and widening operation, and forming a mock seam along the median line of the said reinforcing stripe and said high splice gore.

In testimony whereof, I have signed my name to this specification.

GEORGE P. BOSWORTH.
